LUDWIG SCHÖN, OF ESSEN, GERMANY, ASSIGNOR TO FRIED. KRUPP AKTIENGESELLSCHAFT, OF ESSEN-ON-THE-RUHR, GERMANY.

DEVICE FOR ELECTROMAGNETICAL QUENCHING OF LIGHT ARCS APPEARING UPON THE INTERRUPTION OF AN ELECTRIC CIRCUIT.

Application filed September 3, 1920. Serial No. 408,103.

To all whom it may concern:

Be it known that I, Dr. LUDWIG SCHÖN, residing at Essen, Germany, a citizen of the German Republic, have invented a certain 5 new and useful Improvement in a Device for Electromagnetic Quenching of Light Arcs Appearing upon the Interruption of an Electric Circuit, of which the following is a specification.

10 The present invention relates to a device for quenching light arcs appearing when an electric circuit is interrupted, said device being provided with spark horns which are intended to lead away the light arcs. The 15 purpose of the invention is to provide such a device which is distinguished by the exceedingly small dimensions of the switch, used for the interruptions, and its advantageous action, and which is further intended to 20 quench the light arcs in an alternating current by means of a continuous current magnet field.

In the accompanying drawing is shown, diagrammatically, a hand operated switch, 25 which is provided with a device illustrating one embodiment of the present invention, of which—

Fig. 1 is a longitudinal section; and

Fig. 2 is a top plan view of Fig. 1.

30 A and B are two prismatic carbon pieces with rectangular sides, which may abut against each other with their upright sides a^1 and b^1 , thereby forming the contact pieces of the switch. These contact pieces A and 35 B are connected to a continuous current source feeding a current consumer by means of conductors, not shown. Contact piece A is secured on rod a^2 and contact piece B on a rod b^2 (see Fig. 1). These rods a^2 and b^2 40 are constructed of non-magnetic material. Rod a^2 extends with its free end into a suitable recess in a rectangular frame C, with which it is rigidly connected. Rod b^2 , on the other hand, is slidably carried in the frame 45 C and is, at its other end, provided with a handle b^4 , by means of which it may be drawn out in the direction of arrow x , Fig. 1.

On the upper side of each contact piece A 50 and B are secured spark horns a^3 and b^3 , commencing near the abutment faces a^1 and b^1 , these spark horns being bent out at right angles in the manner indicated in Fig. 1.

On the longitudinal sides of the frame C,

which runs at right angles to the abutment faces a^1 and b^1 , are secured, opposite to each other, two pole-cores c^1 and c^2 , which are covered with exciting windings c^3 and c^4 . These exciting windings c^3 and c^4 are fed by a continuous current. The pole-cores c^1 and c^2 are arranged in such a manner that their upright, symmetrical planes are situated in the same vertical plane as the abutment faces a^1 and b^1 of the closed switch. On both sides of the spark horns a^3 and b^3 are provided two perpendicular, semi-circular disks c^5 and c^6 , which are secured to the free pole faces of the pole-cores c^1 and c^2 by means of downwardly directed stays. The semi-circular disks c^5 and c^6 consequently form parts of pole-shoes for the blow-out magnets c^1 c^3 c^5 ; c^2 c^4 c^6 . The semi-circular disks c^5 and c^6 are so located that their horizontal diameters fall in the plane of the upper surfaces of the spark horns a^3 and b^3 .

75 In describing the operation of the present device, it will be first supposed that the switch is in closed position, as shown in the drawing, and that an electric current is flowing over the interrupting place, which is now 80 bridged over by the contact pieces A and B; and furthermore, that the magnet-windings c^3 and c^4 are being excited. A magnetic field will consequently be generated in the frame C, the lines of force of which close 85 in the manner indicated in Fig. 2 by the dot and dash lines. In order to break the current, the contact piece is quickly moved in the direction of the arrow by means of a pull on the handle b^4 (see Fig. 1). Through this 90 movement of the contact piece B, an electric arc will appear between the abutment faces a^1 and b^1 of the contact pieces A and B, which now stand apart.

This electric arc is immediately driven 95 away from its place of generation by the magnetic field which runs at right angles to the direction of the arc; the course of the magnetic field being so selected that the light arc will be driven upwards. As a consequence, the light arc very quickly will 100 reach the upper edges of the abutment faces a^1 and b^1 . Up to this moment the action of the quenching device of the present invention does not differ from other well-known 105 similar devices.

Directly the light-arc has reached the upper edges of the abutment faces a^1 and b^1 ,

it comes within reach of the magnetic field, which is passing between the disks c^5 and c^6 , and will thereupon be driven off by the latter. It now passes with its base points 5 onto the spark horns a^3 and b^3 and is further conducted on the latter with great speed. As the lines of equal force density in this 10 part of the magnetic field form concentric half-circles with the disks c^5 and c^6 , the light arc similarly takes semi-circular shape. Its length increases then very rapidly and it disappears consequently at the latest, when its base points reach the ends of the spark horns a^3 b^3 .

15 The principal advantage of the present invention resides therein, that the light arc is forced to follow, with great regularity, a well-decided, prearranged course, and to proceed thereon with great rapidity, from the 20 moment its base points have arrived on the upper edges of the abutment faces a^1 and b^1 . The speed with which the light arc is driven off and quenched is then so great, as shown by numerous experiments, that all in- 25 admissible heating is avoided with certainty in every portion of the switch, even with very strong currents, as for instance, 7000 A. 550 V. in a switch for 75 A. continuous current. Even if the current is so strong— 30 as for instance, during short-circuiting in a line—that the light arc, in spite of its semi-circular shape, cannot immediately disappear, when its base points arrive at the free ends of the spark horns, there occurs no 35 damage to the switch parts. As the current first runs radially from the ends of the spark horns, actuated by the magnetic field, and thereupon closes in an increasing semi-circle until it finally disappears, only very small 40 molten beads will appear, even in this case, at the ends of the spark horns, as has been proved by numerous experiments, because these places evidently form somewhat longer base points for the light arcs than the other 45 places.

The great speed with which the light arc is driven off and quenched, as already mentioned several times, makes it possible to interrupt, without danger for the switch, alternate currents with continuous current, 50 magnetic fields. The time within which the alternate-current light arc is driven off and quenched is much shorter than the duration of a half period, and, as a consequence, no 55 danger will arise of the light arc remaining stationary. The possibility of quenching a light arc from an alternate current with a continuous current magnet field is furthermore of very great importance, because the 60 quenching of a light arc from an alternate current by means of an alternate current magnet field is practically impossible.

Still another advantage is gained from the 65 present invention, namely, that the switch path need not be appreciably greater

than the spark space of the highest possible tension in use. Aside from other mechanical advantages, the small necessary switch path is also desirable when the switch is actuated electromagnetically. The size of the electro- 70 magnet needed for the release of the switch may be made very small.

Without deviating from the nature of the present invention, it would be possible to make such arrangement that the lines of 75 equal force density for the field passing between the disks, obtain a different form than the semi-circle. This is particularly desirable when it is required to drive out the light arc very far to one side. Lastly, the 80 spark horns, situated between the disks, may be given a different direction than the one indicated in the drawing, but the arrangement of the spark horns shown is, however, the most advantageous and the preferred 85 construction.

Claims—

1. In apparatus of the character described the combination of a pair of separable contacts and opposing magnet cores in the plane 90 of the meeting face of the contacts and having parallel, disc-shaped pole shoes, the contacts having fixed thereon oppositely curved arcing horns arranged between the pole shoes, said arcing horns including an angle 95 of 180°.

2. In apparatus of the character described the combination of a pair of separable contacts and opposing magnet cores in the plane 100 of the meeting face of the contacts and having semi-circular parallel, disc-shaped pole shoes, the contacts having fixed thereon oppositely curved arcing horns arranged between the pole shoes, said arcing horns including an angle of 180°.

3. In apparatus of the character described the combination of a pair of separable contacts and opposing magnet cores in the plane 110 of the meeting face of the contacts and having semi-circular parallel, disc-shaped pole shoes, the contacts having fixed thereon oppositely curved arcing horns arranged between the pole shoes, said arcing horns including an angle of 180°, said semi-circular 115 pole shoes being so located that their horizontal diameters fall in the plane of the upper surfaces of said arcing horns.

4. In combination with the set of contacts of a switching system, arcing horns opposingly directed and mounted substantially contacting on said contacts, the direction of said horns being substantially that of the direction of separation of said contacts, and a magnetic blow out system comprising pole shoes having an end face substantially parallel with the arc carrying surface of said horns.

5. In combination with the set of contacts of a switching system, arcing horns oppositely directed and mounted substantially 130

contactingly on said contacts, and a magnetic blow out system comprising pole shoes having an end face substantially parallel with the arc carrying surfaces of said horns, 5 said pole shoes offering an increasing magnetic density both toward the contacting point of said contacts and toward said end faces.

6. A direct current blow out system for 10 alternating currents having in combination with the set of contacts of an alternating current system, arcing horns oppositely directed and mounted substantially contactingly on said contacts, and a direct current 15 magnetic blow out system comprising pole shoes having an end face substantially parallel with the arc carrying surfaces of said horns, said pole shoes offering an increasing magnetic density toward the contacting 20 point of said contacts.

7. A current disrupting system comprising a magnetic circuit, a blowout system, arcing horns mountingly directed across said magnetic circuit, the direction of said

horns being substantially at right angles to 25 the flux density distribution lines in the neighborhood of said arcing horns.

8. A current disrupting system comprising arcing horns arranged at an angle of substantially 180° with respect to each other, 30 and a magnetic blowout means giving a flux density distribution of circular type with the said horns forming substantially a diameter for said circular system.

9. A current disrupting system comprising 35 arcing horns directed radially away from each other from a given center, and a magnetic blowout means with pole shoes, said pole shoes being distanced apart to give a blowout arc along a circular locus 40 having the above given center.

The foregoing specification signed at Essen, Germany, this 18th day of May, 1920.
